(57) **CLAIM**

The ornamental design for a baby spoon, as shown and described.

DESCRIPTION

FIG. 1 is a perspective view of a baby spoon design showing my new design.

FIG. 2 is a front view of a baby spoon.

FIG. 3 is a rear view of a baby spoon.

FIG. 4 is a left side view of a baby spoon.

FIG. 5 is a right side view of a baby spoon.

FIG. 6 is a top view of a baby spoon; and,

FIG. 7 is a bottom view of a baby spoon.

The broken lines in the drawings depict portions of the baby spoon that form no part of the claimed design.

1 Claim, 7 Drawing Sheets
